EASY BREAK TABLET

Edwin F. Roberts, Stamford, Conn., assignor to Ives
Laboratories, Inc., New York, N.Y.

Continuation of abandoned design applications Ser. No.
185,460 and Ser. No. 185,467, both Sept. 30, 1971.
This application Oct. 10, 1972, Ser. No. 296,386

Term of patent 14 years

Int. Cl. D28—01; D1—01
U.S. Cl. D16—3

FIG. 1 is a top plan view of a easy break tablet embodying my new design;

FIG. 2 is a side elevational view thereof taken at lines 2—2 of FIG. 1;

FIG. 3 is a side elevational view taken at lines 3—3 of FIG. 1;

FIG. 4 is a sectional view taken along lines 4—4 of FIG. 1;

FIG. 5 is a top plan view of a easy break tablet embodying a second modification of the form illustrated in FIG. 1;

FIG. 6 is a side elevational view taken at lines 6—6 of FIG. 5;

FIG. 7 is a side elevational view taken at lines 7—7 of FIG. 5;

FIG. 8 is a sectional view taken along lines 8—8 of FIG. 5;

FIG. 9 is a top plan view of a easy break tablet illustrating a third embodiment of my new design illustrated in FIG. 1;

FIG. 10 is a side elevational view thereof as seen at right angles to FIG. 9;

FIG. 11 is a sectional view as seen along either of lines 11—11 of FIG. 9;

FIG. 12 is a top plan view of a easy break tablet embodying a fourth modification of the form illustrated in FIG. 1;

FIG. 13 is a side elevational view of the embodiment of FIG. 12 as seen at right angles to FIG. 12; and

FIG. 14 is a sectional view as seen along either of lines 14—14 of FIG. 12.

This is a continuation of design application Ser. Nos. D. 185,460 and D. 185,467, both filed Sept. 30, 1971, and now abandoned.

I claim:

The ornamental design for an easy break tablet, as shown and described.
